UNITED STATES PATENT OFFICE.

LAURENCE E. TOPHAM, OF SWAMPSOFT, MASSACHUSETTS, ASSIGNOR TO UNITED SHOE MACHINERY CORPORATION, OF PATERSON, NEW JERSEY, A CORPORATION OF NEW JERSEY.

PATTERN-COPYING MACHINE.

Application filed December 10, 1920, Serial No. 429,719. Renewed December 20, 1926.

This invention refers to pattern copying machines and is disclosed as embodied in a lathe for turning shoe lasts.

Great difficulty has been experienced in cutting lasts from a single model by means of the ordinary width grading mechanism in that the width grading mechanism magnifies the distance from the axis of rotation of the last to the surface by the same multiplying factor throughout the last and thereby effects the result of making the sole profile of a wider last than the model more convex than that of the model since the lower part of the ball is farther from the axis than any other part of the sole profile and is consequently dropped farther below the axis by the width grading mechanism. Such variations in lasts have no anatomical justification and various methods of correcting the difficulty, such as the use of heels of anomalous heights, and the empirical bending of a wide last by sawing slots in the top and bottom and wedging one slot until the other closes, have been adopted. Such expedients are very expensive and unsatisfactory and it is difficult to obtain uniform results by their use. The invention of Leland B. Whipple disclosed and claimed in United States Letters Patent No. 1,362,183 granted Dec. 14, 1920, on his application and further improved by the invention of Stanley E. Boynton, disclosed and claimed in United States Letters Patent No. 1,362,185 granted Dec. 14, 1920 on his application for U. S. Letters Patent Serial No. 234,012, filed May 11, 35 1918, effected a solution of the problem by moving the model transversely to its axis of rotation in the last lathe during the last cutting. It is obvious that (neglecting width grading for the time being) the transverse section of a model which is being reproduced in the block at any instant will be reproduced in the block in the same relation to its axis of rotation as is occupied by the model section in relation to its mechanical axis of rotation, 40 assuming that we are dealing with a machine of the ordinary Gilman type. Any transverse displacement of the model from normal position relatively to its mechanical axis of rotation will therefore displace the block section being formed by the same amount upon its mechanical axis of rotation. A continuous control of the model positions involving movement of the model back and forth in a

direction perpendicular to its tread surface will therefore enable the sole profile of the last cut to be controlled in any desired manner. Obviously any profile can be controlled in the same way by moving the model in the plane containing the mechanical axis of revolution and the profile to be controlled. 55

While the above-described mechanism as constructed by Whipple and Boynton was quite successful, it was found that under certain conditions of work, for example, the necessity of extraordinarily tight clamping of worn models between the model dogs, the slides which effected the lateral movement of the model did not always work as smoothly as is desirable, and an important object of the present invention is still further to improve the art of last cutting by providing a machine by means of which such occasional difficulty may be avoided. I have discovered that the effect of moving the model according to the invention of Whipple can be exactly produced by mounting the model in the ordinary well-known manner and moving the center of the model wheel in a circle the plane of which is perpendicular to the axis of rotation of the model and the radius of which is equal to the displacement of the model from normal position in a machine built according to the Whipple invention, this radius being of course variable as the cutting proceeds along the length of the last. An important feature of the present invention is, therefore, a mechanism for effecting a revolutionary movement of the model wheel spindle and preferably a revolutionary movement of variable radius during the last cutting. This object is secured in the illustrated machine by a variable throw eccentric controlled preferably by a cam, and operated in time relation to the rotation of the model. 65

It is essential that the revolutionary movement of the model wheel spindle keep step exactly with the rotational movement of the model in order to avoid errors in reproduction. Accordingly an important feature of the invention consists in means for maintaining the relation between these movements, irrespective of the swing frame movement. In the machine shown this is accomplished by a pair of spiral gears between the two rotating objects, the angle of the teeth of which is so adjusted that a rotation of the swing frame 70

is absorbed in the relative movement of the spiral gears without disturbance of the two angularly moving objects.

Another important object of the invention relates to the alteration in the transverse shape of the last reproduced from the model. It has long been the custom in many factories in width grading a set of lasts to use the same insole pattern for the A and AA widths and 5 for the E and EE widths in order to avoid too extreme an appearance of narrowness or width in these extreme lasts. The EE last, for example, must nevertheless have the normal EE foot room in it and therefore can not 10 be graded in the last lathe in the ordinary way. The last is ordinarily produced by grading a last having a larger amount of room in it than the EE and then trimming off 15 the bottom by hand to fit the E insole pattern, the whole operation being so performed that 20 the trimmed last will have the EE girth measurements. This operation obviously requires great skill, is essentially a matter for the model maker rather than the last turner and 25 is consequently extremely expensive. I propose, among other objects of invention, to remedy this difficulty by a novel grading mechanism which in the machine shown provides a factor of magnification which is variable 30 during a rotation of the last. By this means the magnification factor can be held for example at unity while the model wheel is rolling over the tread face of the model so that the tread face of the model will be 35 produced exactly in the block and the magnification factor can then be made other than unity during the reproduction of other portions of the last, whereby the required foot room may be created in it, although the shape 40 and geometrical relation of the cross-section to that of the model are varied. In the machine shown this object is secured by a continuous cam operated control of the width grading magnification factor, which, in the 45 particular problem suggested, adjusts the width grader for 1:1 reproduction as the model wheel passes over the tread face of the last, and adjusts it to compensate for the omission of grade across the latter, as it passes 50 around the remainder of the last.

These and other features of the invention comprising various combinations and arrangements of parts will be better understood from the following description of a preferred 55 embodiment thereof selected for purposes of illustration and shown in the accompanying drawings in which,

Fig. 1 is a plan of the essential portion of the machine;

Fig. 2 is an enlarged detail of the model wheel control mechanism;

Fig. 3 is a partial elevation of the left hand end of the machine;

Fig. 4 is a vertical section on the line 4-4 65 of Fig. 2;

Fig. 5 is a vertical section on the line 5-5 of Fig. 1;

Figs. 6, 7 and 8 are enlarged diagrams of the width grading mechanism in several positions;

Fig. 9 is a partial elevation of the right end of the machine arranged for ordinary width grading;

Fig. 10 is an enlarged detail of the "ordinary" width grading unit;

Figs. 11 and 12 are diagrams illustrating the profile control;

Figs. 13 and 14 are a plan and elevation of an alternative form of model wheel control mechanism; and

Fig. 15 illustrates diagrammatically the swing frame construction of the ordinary lathe.

The bed 10 of the machine is of ordinary construction and need not be further described here. It is furnished with a flat rear slideway 12 and two front V-shaped guides 14, 16 co-operating with suitable recesses in the model wheel carriage 18 and cutter carriage 20, respectively. The cutter carriage 20 is provided with a sliding plate 22 working in rectilinear guides crosswise of the machine which carries the motor 24 and the cutter head 26 on the spindle 28 inclined substantially 30° toward and with the direction of feed of the cutter carriage, as is described in United States Letters Patent No. 1,330,841, granted Feb. 17, 1920, upon the application of Frank S. Buck. The slide 22 is for the purpose of width grading, as will be explained later. It has mounted at its rear a roller 30 upon a vertical axis and a spring 32, with its forward end abutting upon the carriage 20, and its rear end upon the slide 22 tends to force the slide into a rearmost position. The carriages 18 and 20 may be driven in any appropriate manner and may be joined by any appropriate type of length grading mechanism. Inasmuch as this invention is not concerned with the performance of length grading, such mechanism is not shown.

A swing frame 34 is pivoted at the top of the machine, as is well understood by experts in this art, the construction being common in the well-known Gilman last lathe. The lower end of the swing frame is connected by links 36 to an arm 38 connected with a counterweighted rockshaft, as is also well understood, for the purpose of forcing the swing frame to operative position. The swing frame carries model and block holding dogs 40 and 42, respectively, the drive spindles of which are connected for equal rotation in any desired manner, as will also be well understood, such construction being common. The 120 rotational axes of the dogs are hereinafter alluded to as the "mechanical axes of rotation" of the model or block respectively, by which is meant that they are fundamentally related to the machine and not to what rotates on 130

them. The swing frame 34 may be replaced by a slide frame sliding on rectilinear guides, if desired, without departing from the present invention.

5 The model wheel carriage 18 has two pairs of vertical guides 44 and 46 between which, in a close machine fit, is slidably mounted the frame 48. Upon the front end of this frame is mounted a member 50 having two studs 51 and 53 which are offset and upon the outer stud 53 of which is mounted the model wheel 52. The member 50 may be replaced by other similar members having more or less offset between the two studs in order to accommodate model wheels of different diameters with their operative faces 54 at the same point for the purpose of securing more accurate reproduction of sharp corners during width grading. This construction is well known in the 10 Gilman last lathe and need not be described further.

The frame 48 carries two sets of gimbals each comprising a frame 56 carried upon horizontal, collinear opposed spindles 58 mounted in the frame 48, which frame 56 has mounted within it upon collinear opposed vertical spindles 60, at right angles to the spindles 58, a frame 62, in which is mounted with an accurate turning and sliding fit a rod 64. The rod 64 is integrally mounted with and between two collinear spindles 66, but is staggered with respect thereto and preferably has its middle point in the axis of the two spindles 66. The spindles 66 and rod 64 form a Z-shaped member. The rods 64 are longer than the thickness of the frame 62 so that they can be moved through the frames 62 a certain distance. This is permitted by movement of a slide 68 movable lengthwise of the machine in ways 70 upon the carriage 18, as shown in Fig. 4, which slide carries the standards 72 and 74 in which the spindles 66 are mounted. When the slide 68 is in such position that the centers of the rods 64 lying on the axis of the spindles 66 are at the center of the frames 62, the rotation of the spindle 66 and rods 64, which is accomplished through equivalent gears 76 and 77 meshing with an idler 78 mounted upon the two spindles 66 50 and a third spindle 80 respectively, all in the standard 74, will cause no movement of the frame 48 in the guides 44 but will simply rock the gimbal mechanism 56, 62. If, on the other hand, the slide 68 is moved from this 55 position to such a position as is shown in Fig. 2, the rotation of the gears 76 will cause a bodily movement of the frame 48, all parts of the frame remaining parallel to themselves, and will cause the center of the model wheel 52 to describe a circle, the radius of which is equal to the eccentricity of the center of the frame 62 relatively to the axis of the spindles 66.

60 In other words, I have described and shown a variable eccentric mechanism for revolving

the center of the model wheel in a circle of varying radius during the cutting of the last, the plane of said circle being perpendicular to the axis of rotation of the model. Any convenient mechanism for accomplishing this 70 mechanical result may be substituted for the frame 48 and its operating parts without departing from the present invention. The position of the model wheel center corresponding to the neutral adjustment of the slide 68, 75 when the radius of the movement of the model wheel center is zero, is the normal position of the model wheel center in the lathe as understood prior to the present invention. The longitudinal axis passing through this 80 position has been termed in the claims a "mechanical axis of revolution" since the variable eccentric mechanism described effects a revolution of the model wheel center around it, though the variable eccentric mechanism is 85 displaced from it for the sake of mechanical convenience. The significance of the term "mechanical" is that the axis is related to the machine rather than to the model wheel.

The slide 68 is operated by a link 82 one end 90 of which is pivoted to the slide and the other end of which is adjustably pivoted in a slot in a lever 84, a second fulcrum of which is mounted upon the carriage 18 at 86, and the third fulcrum of which is connected by a link 88 to a bell-crank lever 90 whose center fulcrum 92 is also on the carriage 18. The other extremity of this bell-crank carries a roller 94 which contacts with a cam 96 upon the bed 10. As the model wheel carriage 18 moves to the left in Fig. 2, this roller, which is forcibly held in contact with the cam 96 by the spring-pressed plunger 98 mounted in the carriage 18, will operate the slide 68 in any desired manner, according to the shape of the cam 96, 100 and thereby control the radius of eccentricity of movement of the model wheel rotational axis 53. The gear 77 has integrally mounted with it a gear 100 which is wide enough to remain in contact with a pinion 102, irrespective of the position of the slide 68, the pinion 102 being mounted upon the carriage 18 and splined upon a shaft 104 extending through the frame of the machine to the disk 166, the purpose of which will appear later. 110

The utility of the above described mechanism in controlled profiles of the objects produced will be readily understood. It is evident that the depth of cut upon the block at any instant depends solely upon the distance between the mechanical axis of rotation of the block and the cutter axis, or, aside from the matter of width grading, what is the same thing in an ordinary machine of the Gilman type, the distance between the mechanical axis of rotation of the model and the axis of rotation of the model wheel. In the Whipple-Boynton machine above mentioned, the 120 toe spring control effect was produced as 125

above noted, by shifting the model "up or down" upon its mechanical axis of rotation in the swing frame so as to alter the distance between the mechanical axis of rotation of the model and the axis of rotation of the model wheel. Now it is obvious that the same effect will be produced upon the distance between the axes of rotation of the block and cutter, by (1) shifting the model upon its mechanical axis of rotation and letting the swing frame move until the model wheel contacts with the surface of the model as in the Whipple-Boynton machine, or (2) leaving the model undisturbed in the swing frame and moving the axis of rotation of the model wheel from its normal position an amount equal to the displacement of the model in the Whipple machine, but in the opposite direction. The ordinary axis of rotation of the model, that is, the line joining the toe tip to the center of the heel is moved in the Whipple-Boynton machine in a circle around the mechanical axis of rotation of the model as the model makes each rotation and therefore the same effect upon the last cutting will be produced by revolving the axis of rotation of the model wheel about its normal position in a circle of the same radius in the same direction at the same speed, but differing 180° in phase. This is illustrated in Figs. 11 and 12 in which the full line contour A represents the normal position of the model section and the dotted contour B represents the displaced position of the model section at the instant of reproduction, in such a machine as that of Whipple, the displacement being measured by the distance d , the mechanical axis of rotation of the model and block being at a , and the position of the model wheel and cutter being shown by the circle C with center at b . Obviously the same separation ab between the axis of rotation of the block and that of the cutter will be produced by moving the center of the model wheel the same distance d , in the opposite direction and leaving the model in the A position, the center of the cutter remaining at b . In other words, the change described consists simply in moving the figure consisting of the model section and the model wheel as a whole parallel to itself the distance d relatively to the mechanical axis of rotation of the model in the swing frame and relatively to the normal axis of rotation of the model wheel, respectively, which will not move the swing frame or affect the relation of the block and the cutter in any way.

In another way of looking at the matter, regarding the model as an object fundamentally related to its own longitudinal axis running from its toe tip to the heel center (the last cut being generated in a fundamental relation to a similar axis) the Whipple-Boynton machine controls a longitudinal profile of the last cut by revolving the model

bodily in a circle about its mechanical axis of rotation in the swing frame, the radius of the circle being the distance from the mechanical axis to the longitudinal axis mentioned. This radius being denoted by d , the depth of cut in the block will be affected by the quantity $d \sin \theta$ where θ is the amount of revolution of the model measured from a definite starting point. The machine of the present invention bodily revolves the model wheel in a circle of radius d , thus producing the same effect upon the relation of the cutter and block.

It should be understood that the phrase "revolution of the model wheel" and the like really refer to the revolution of the model wheel center 53, and such expressions have been adopted to avoid circumlocution. The rotation of the model wheel about its center 53 is merely an anti-friction device, and has nothing theoretically to do with the reproduction function of the machine. The radius of revolution of the model wheel center will be normally less than one-half inch, and the greater part of the model wheel will consequently not revolve around the "mechanical axis of rotation," as far as its movement necessary for reproduction is concerned. The model wheel is a wheel only because the cutter is of that form. If the cutter were a point the model wheel would also be a point, and the language used would be rigorously accurate.

The shaft 80 which drives the gear 78 is splined in a miter gear 108 mounted in the standard 110 on the main bed of the machine. This miter gear is driven by a second miter gear 112 mounted in a yoke 114 pivoted on the shaft 80 and upon a shaft 116 splined in a spiral gear 118 mounted in a frame 120 pivoted at 121 on the model spindle 122 on the swing frame 34. A pinion 124 meshing with the spiral gear 118 and pivoted also at 121 transmits power from the pinion 123 on the spindle 125. The spindle 125 is driven by the pulley 125^a from the head of the swing frame in the ordinary manner. The splines in the shafts 80 and 116 permit free movement of the slide 68 and of the swing frame.

For accurate reproduction in a last lathe it is necessary that all points in the intersection of a plane passing through the axis of rotation of the model with the surface of the model (or of a "radial section" of the model) should contact with the model wheel in the same way; or in another view of the matter, if the machine were at rest and the model should expand by the movement of all its surface points straight out from the axis of rotation, the point which was in contact with the model wheel should remain in contact with it during the expansion. This offers no difficulty where a slide frame is used, but under some conditions of work a slide frame is not sufficiently lively and responsive and a swing frame must be used. The rotation of

the swing frame in following the expanding model tends to move the radius drawn to the original point of contact off the model wheel. This problem is illustrated in Fig. 15. The 5 pivot of the swing frame 190 is represented at 192, and the axis of rotation of the model at 194. The center of the model wheel 195 is shown at 196 and the distance 194-196 is the radius of the model wheel. The triangle 10 192-194-196 therefore represents the condition of things when the axis of revolution of the model lies on the face of the model wheel, which sometimes occurs for example at the upper side of the toe of a woman's last. 15 Now suppose the swing frame to remain fixed, and the machine to swing around it as the model wheel slides parallel to its axis, by means of its sliding carriage—the model remaining at rest in the swing frame—until the 20 model wheel reaches the point, this point, and the axis containing the first point of contact, defining a radial section which is most distant from the axis of rotation. The model wheel center will then move to a point 198. For perfect reproduction the points 196, 198 and all 25 positions of the model wheel center lying between them should lie on a straight line passing through the axis 194. The locus of all these positions is actually the arc 200, and 30 the distance 192-196 is so adjusted that this arc fits the line 194-196 as closely as possible. It has been found advisable in practice to adjust this distance so that the arc 200 crosses the line 194-196 between the points 196 and 35 198 which represent the extreme points of swing, as shown in Fig. 15. In the Gilman 10-inch cutter head lathe and 3½ inch cutter head lathe, the dimensions are respectively

40	192-194.	192-196.
10-inch.....	34"125	33"625
3½ inch.....	33"719	33"625

45 In turning a left last from a right model, the dogs are so set that the model and last come to alignment on the line (or radial plane) 194-196, and turn equally away from it in both directions.

50 The preceding discussion forms no part of the present invention, and its theory has been known for many years, but it must be perfectly understood in order to understand the next feature of the present invention to 55 be described. In the ordinary lathe it is only necessary that the model and block rotate equally away from the line 194-196 in equal times—uniformity or any particular rate of rotation is of no consequence nor is 60 it of consequence in the simpler problem of turning a right last from a right model. In practicing the present invention, however, it is necessary that the rotation of the model follow exactly the revolution of the model 65 wheel center. This is accomplished by ad-

justing the slope of the teeth in the gears 118 and 124 so that a movement of the swing frame will not in itself tend to drive the shaft 80. This is accomplished practically by laying out on the drawing board the 70 mechanism shown in Fig. 3 in the two positions of maximum and minimum swing of the swing frame. The latter will be the position in which the model wheel face is on the axis of the spindle 122. These layouts will 75 show how much and in which direction the shaft 116 is obliged to rotate on its own axis during the swing frame movement, due to the engagement of the gear 108 (regarded as fixed) and the gear 112, and also how 80 much and in what direction the gear 118 moves at the same time about the center 121, and the slope of the teeth in the gear and pinion 118-124 can then be adjusted so that the rotation of the gear 118 due to its being 85 splined on the shaft 116 will just permit it to move around the center 121 the proper amount without disturbing the gear 124. Thus the timing of the model wheel center 90 revolution is not affected by the changes in position of the swing frame due to varying model radii.

Figs. 13 and 14 show an alternative and, from some points of view, preferable construction of the model wheel operating mechanism. In this form, the slide 68 is done away with and thereby all difficulties incidental to the friction of impending slipping which is relatively great as compared with that of actual slipping are done away with, 95 so that a change in the eccentricity of the model wheel movement will be more smoothly produced. The standards 126 are mounted directly upon the carriage 18. The rods 64^a are oppositely inclined instead of parallel 100 and are moved by a rocker lever 128 fulcrumed at 130 upon the carriage 18 by the cam 96, cam roll 94, lever 90^a, adjustably pivoted at 92^a and link 132 and crank arm 134 mounted upon the spindle at 130. The 110 rocking lever 128 moves the two rods 64^a in opposite directions and therefore their opposite inclination produces the same eccentricity of movement of the frame 48, the performance of the machine being the same as 115 before.

The novel width grading mechanism will now be described. The roller 30 rests against the face of a long plate 136 which extends along behind the cutter carriage parallel to the length of the machine and forms one arm of a bell-crank lever pivoted on a horizontal axis at 138, the other arm of which is seen at 140, Fig. 9. The rocking of this bell crank through the reaction between the plate 136 and the roller 30 which contacts with it irrespective of the location of the cutter carriage 20 along the last, operates the slide 22 and effects the width grading function. The mechanism for operating the plate 136 is as 130

follows:—Pivoted at 142 on the main frame of the machine is a segment plate 144 having a graduated slot 146 in which may be adjusted at will the end of a link 148, the other 5 end of which is yoked around the upper end of another link 150, there being a cam roller 152 at the joint. The lower end of the link 150 is pivoted at 151 to the end of the arm 140, already described. Pivoted at 154 on a 10 vertical bar 156 bolted to the bed of the machine is a swinging arm 158, the upper end of which is connected by a link 160 with the swing frame 34. The link 158 carries an integral segment shaped lever 162 which 15 operates with the roller 152 and is formed preferably in the arc of a circle, the center of which falls at the junction of the arm 140 and link 150, when the swing frame is so positioned that the axis of rotation of the 20 model lies upon the face of the model wheel. Movement of the swing frame in and out corresponding to the varying contour of the model will rock the arm 158 and consequently the segment 162. If the cam roller 152 lies 25 directly over the center 154, as shown in Fig. 6, no motion of the link 150 and plate 136 will result and no width grading will be done. If, however, the roller 152 is displaced from the center 154, the rocking of the segment 30 162 will move the bar 136 and effect a width grading action in the cutting. The segment grading lever 162 is in effect a fan-board, the contacting finger for which is the cam roller 152, and in ordinary width grading 35 the roller 152 would remain at the same position on the fan-board. The present invention, however, provides that the position of the cam roller 152 may be continuously controlled so as to vary the width grading 40 multiplying factor at will during the last cutting. This is effected preferably by a cam 164 mounted upon a disk 166 which is driven by the shaft 104, as already stated. The gearing is so proportioned that the disk 45 166 rotates at the same angular velocity as the model and block. The cam 164 co-acts with the cam roller 170 upon the end of the segment 144 and thereby rocks the segment 144 about its center 142 in a cycle of the same 50 period as the model rotation. The segment 144 in rocking moves the cam roller 152 through the link 148 and thereby controls continuously during each rotation of the model the distance from the center 154 to the 55 center of the roll 152 which is equivalent to controlling the width grading multiplying factor. The link 148 is exactly the length of the distance between the centers 154 and 142, which is also the radius of the segment 60 144, so that if the end of the link 148 is adjusted so as to be directly over the center 142 (the zero setting for width grading) the roller 152 will be directly over the center 154 and no width grading will be done, irrespec- 65 tive of the movements of the segment 144.

On the other hand, it is possible by a particular design of the cam 164 to swing the segment 144 into such a position that its center of curvature will be held at the point 154 so that the roll 152 will lie over the center 70 154, regardless of the adjustment of the end of the link 148 in the slot 146. This position is shown in Fig. 6. For the purposes of the particular problem which gave rise to the construction of the disclosed machine, the 75 cam 164 is designed, for example, with a portion 172 of substantially circular formation and so positioned as to keep the segment 144 substantially motionless in the position shown in Fig. 6 while the sole of the model 80 is rolling over the model wheel. No width grading whatever will therefore be done during the reproduction of the tread surface of the model. The remainder of the cam at 85 174 is so designed as to swing the segment 90 sufficiently to displace the roller 152 from the center 154 enough to make up the failure to width grade the bottom of the last while going around the upper portion so that the required girth of the wider last to be cut will 95 be secured, although the bottom is not width graded at all. The same insole pattern will therefore fit both the model and the last being cut. The cam 164 may be designed to effect 100 variations in the width grading magnification factor according to any desired rule. The cam shown in Fig. 6 would grade a whole series of widths with the same insole pattern by simply adjusting the link 148 in the slot 146 for each last cut. The substitution of a 105 new model, with a different insole pattern, would provide a new set of widths having the insole pattern of the new model.

The length of the link 148 is equal to the 110 distance between the centers 142 and 154 so that the setting of the link 148 in the slot 146 will not effect the cessation of width grading across the bottom of the last, though in general the width grading multiplying factor is 115 on the average determined by the setting of the end of the link 148 in the slot 146 in accordance with suitable scale. The curvature of the segment 162 insures that no width grading movement can take place when the axis of the model is on the model wheel face, irrespective of movement impressed on the roller 152.

If it is desired to do ordinary width grading with the machine, the segment 144 must be held motionless. This may be accomplished by means of a circular cam 164, or by a link 176 joining the axes 170 and 104. This link should be of suitable length to hold the segment 144 tilted into substantially the mean position communicated to it by the regular cam 164 and this position with the link 148 suitably adjusted in the slot 146 according to the scale thereon will place the cam roller 152 in the proper fixed position upon the segment 162 to accomplish the desired uniform 125 130

width grading. The link 176 will preferably be made adjustable in length and the two adjustable portions of it, 178 and 180, will preferably be provided with scales 182 and 184, respectively, to show the length requisite to produce the desired width grade in connection with the particular model being used, since it requires a larger magnification factor to grade one width from a child's model than it does to grade one width from a man's model.

Fig. 6, as stated, shows the relation of the parts during the reproduction of the tread face of the model when no width grading is taking place. Fig. 7 shows the condition of things a half revolution later, in which the roller 170 is at the extreme portion 174 of the cam track and width grading is taking place at substantially double the normal magnification rate. Fig. 8 illustrates the condition of things at the time that the upper part of the instep is being reproduced. The cam 174 and the segment 144 are in the same relative positions, but the swing frame has been displaced more than in Fig. 7 in order to accommodate the greater radius vector from the model axis to the top of the instep. The segment 162 is therefore tipped farther and the link 150 is therefore displaced a greater distance, causing a greater movement of the bar 136. In Figs. 6, 7 and 8, the arrows 186 show the displacement of the arm 158 from the position corresponding to a swing frame position with the axis of rotation of the model upon the face of the model wheel, and indicate the radius of the model being reproduced. The arrows 188 show the displacement of the segment 162 from its corresponding position. The arrows 190 show the displacement of the segment 144 from the position in which no width grading is being done, and the arrows 192 show the displacement of the bar 136 from the corresponding position, and show the absolute value of the width grade.

A few words may be said of the performance of the disclosed machine, from the quantitative standpoint. For any given position of the segment 144 the movements of the pivot 151 are substantially proportional to those of the swing frame. If the segment 144 be then moved to a second position, and the swing frame moved to the same series of positions as before, the movements of the pivot 151 in the second set are substantially proportional to the corresponding ones in the first set, the factor of proportionality being the ratio of the two distances 152—154. The movements of the swing frame (or fan board) are in effect multiplied by a factor which is variable during the last cutting and is, in the illustrated machine, cyclical, with a period equal to that of the model rotation. This factor is determined at any instant by the position of the roller 152, and is proportional to the distance 154—152.

Having thus described my invention, what I claim as new and desire to secure by Letters Patent of the United States is:—

1. In a pattern copying machine, four principal instrumentalities, viz, a model wheel, a model holder, a cutter and a block holder, four mechanical axes to which these instrumentalities are respectively related, the distance between the cutter and block holder axes being controlled by the distance between the model wheel and model holder axes as determined by contact between the peripheries of the model wheel and a model held in the holder, and means for revolving one of the model wheel and cutter, displaced from its normal position relatively to its mechanical axis, about the mechanical axis.

2. In a pattern copying machine, four principal instrumentalities, viz, a model wheel, a model holder, a cutter and a block holder, four mechanical axes to which these instrumentalities are respectively related, the distance between the cutter and block holder axes being controlled by the distance between the model wheel and model holder axes as determined by contact between the peripheries of the model wheel and a model held in the holder, and a cam and connections for revolving one of the model wheel and cutter, displaced from its normal position relatively to its mechanical axis, about the mechanical axis.

3. In a pattern copying machine, four principal instrumentalities, viz, a model wheel, a model holder, a cutter and a block holder, four mechanical axes to which these instrumentalities are respectively related, the distance between the cutter and block holder axes being controlled by the distance between the model wheel and model holder axes as determined by contact between the peripheries of the model wheel and a model held in the holder, and means for displacing and revolving one of the model wheel and cutter upon and about its mechanical axis.

4. In a pattern copying machine, four principal instrumentalities, viz, a model wheel, a model holder, a cutter and a block holder, four mechanical axes to which these instrumentalities are respectively related, the distance between the cutter and block holder axes being controlled by the distance between the model wheel and model holder axes as determined by contact between the peripheries of the model wheel and a model held in the holder, and a cam and connections for displacing and revolving one of the model wheel and cutter upon and about its mechanical axis.

5. In a pattern copying machine, four principal instrumentalities, viz, a model wheel, a model holder, a cutter and a block holder, four mechanical axes to which these instrumentalities are respectively related, the distance between the cutter and block holder axes being controlled by the distance between the model wheel and model holder axes as determined by contact between the peripheries of the model wheel and a model held in the holder, and means for revolving one of the model wheel and cutter, displaced from its normal position relatively to its mechanical axis, about the mechanical axis.

holder axes being controlled by the distance between the model wheel and model holder axes as determined by contact between the peripheries of the model wheel and a model held in the holder, and means for revolving the model wheel, displaced from its normal position relatively to its mechanical axis, about the mechanical axis.

6. In a pattern copying machine, four principal instrumentalities, viz, a model wheel, a model holder, a cutter and a block holder, four mechanical axes to which these instrumentalities are respectively related, the distance between the cutter and block holder axes being controlled by the distance between the model wheel and model holder axes as determined by contact between the peripheries of the model wheel and a model held in the holder, and a cam and connections for revolving the model wheel, displaced from its normal position relatively to its mechanical axis, about the mechanical axis, said cam being developed as a function of the longitudinal position in the work of the point being reproduced.

7. In a pattern copying machine, four principal instrumentalities, viz, a model wheel, a model holder, a cutter and a block holder, four mechanical axes to which these instrumentalities are respectively related, the distance between the cutter and block holder axes being controlled by the distance between the model wheel and model holder axes as determined by contact between the peripheries of the model wheel and a model held in the holder, and means for displacing and revolving the model wheel upon and about its mechanical axis, the revolution period being equal to the rotation time of the model.

8. In a pattern copying machine, four principal instrumentalities, viz, a model wheel, a model holder, a cutter and a block holder, four mechanical axes to which these instrumentalities are respectively related, the distance between the cutter and block holder axes being controlled by the distance between the model wheel and model holder axes as determined by contact between the peripheries of the model wheel and a model held in the holder, and a cam and connections for displacing and revolving the model wheel upon and about its mechanical axis, the revolution time being equal to the rotation time of the model.

9. In a pattern copying machine, four principal instrumentalities, viz, a model wheel, a model holder, a cutter and a block holder, four mechanical axes to which these instrumentalities are respectively related, the distance between the cutter and block holder axes being controlled by the distance between the model wheel and model holder axes as determined by contact between the peripheries of the model wheel and a model held

in the holder, and a variable eccentric mounting for the model wheel, whereby the model wheel may be carried bodily around its mechanical axis in a circle of varying radius.

10. In a pattern copying machine, four principal instrumentalities, viz, a model wheel, a model holder, a cutter and a block holder, four mechanical axes to which these instrumentalities are respectively related, the distance between the cutter and block holder axes being controlled by the distance between the model wheel and model holder axes as determined by contact between the peripheries of the model wheel and a model held in the holder, an eccentric of variable throw upon which one of the model wheel and cutter are mounted and a cam and connections for varying the throw of the eccentric.

11. In a pattern copying machine, four principal instrumentalities, viz, a model wheel, a model holder, a cutter and a block holder, four mechanical axes to which these instrumentalities are respectively related, the distance between the cutter and block holder axes being controlled by the distance between the model wheel and model holder axes as determined by contact between the peripheries of the model wheel and a model held in the holder, an eccentric upon which the model wheel is mounted, the axis of the eccentric coinciding with the mechanical axis of the model wheel, and means for driving the eccentric.

12. In a pattern copying machine, four principal instrumentalities, viz, a model wheel, a model holder, a cutter and a block holder, four mechanical axes to which these instrumentalities are respectively related, the distance between the cutter and block holder axes being controlled by the distance between the model wheel and model holder axes as determined by contact between the peripheries of the model wheel and a model held in the holder, an eccentric upon which the model wheel is mounted rotating at the same angular velocity as the model, the axis of the eccentric coinciding with the mechanical axis of the model wheel, and means for driving the eccentric.

13. In a pattern copying machine, four principal instrumentalities, viz, a model wheel, a model holder, a cutter and a block holder, four mechanical axes to which these instrumentalities are respectively related, the distance between the cutter and block holder axes being controlled by the distance between the model wheel and model holder axes as determined by contact between the peripheries of the model wheel and a model held in the holder, an eccentric upon which the model wheel is mounted, the axis of the eccentric coinciding with the mechanical axis of the model wheel, cam operated means for varying the throw of the eccentric, and means for

driving the eccentric, the rotation of the eccentric being at the same angular velocity as that of the model and in the same direction.

14. In a pattern copying machine, four principal instrumentalities, viz, a model wheel, a model holder, a cutter and a block holder, four mechanical axes to which these instrumentalities are respectively related, the distance between the cutter and block holder axes being controlled by the distance between the model wheel and model holder axes as determined by contact between the peripheries of the model wheel and a model held in the holder, a model wheel carriage, guides on said carriage, a plate moving universally in a plane in said guides, said model wheel being mounted on said plate, and a cam and connections for operating said plate in said guides.

15. In a pattern copying machine, four principal instrumentalities, viz, a model wheel, a model holder, a cutter and a block holder, four mechanical axes to which these instrumentalities are respectively related, the distance between the cutter and block holder axes being controlled by the distance between the model wheel and model holder axes as determined by contact between the peripheries of the model wheel and a model held in the holder, a model wheel carriage, guides on said carriage, a plate moving universally in a plane in said guides, said model wheel being mounted on said plate, a rotating shaft having a staggered portion extending through said plate, a bearing for said staggered portion mounted in gimbals in said plate, and a cam and connections for moving said shaft endwise through the plate whereby the staggered portion and the gimbals cause movement of said plate of varying amplitude.

16. In a pattern copying machine, four principal instrumentalities, viz, a model wheel, a model holder, a cutter and a block holder, four mechanical axes to which these instrumentalities are respectively related, the distance between the cutter and block holder axes being controlled by the distance between the model wheel and model holder axes as determined by contact between the peripheries of the model wheel and a model held in the holder, and a variable eccentric mounting for the model wheel comprising a Z-shaped shaft and a gimbal bearing whereby the model wheel may be carried bodily around its mechanical axis in a circle of varying radius.

17. In a pattern copying machine, four principal instrumentalities, viz, a model wheel, a model holder, a cutter and a block holder, four mechanical axes to which these instrumentalities are respectively related, the distance between the cutter and block holder axes being controlled by the distance between the model wheel and model holder axes as determined by contact between the peripheries of the model wheel and a model held in the

holder, an eccentric of variable throw upon which one of the model wheel and cutter are mounted and a cam and connections for varying the throw of the eccentric, the cam being developed as a function of the longitudinal position in the work of the point being reproduced.

18. In a pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder, and a width grading mechanism comprising a fan-board, a contact member co-operating with the fan-board and connected to one of the said instrumentalities to cause width grading movements thereof, and means for automatically varying the setting of the member on the fan-board.

19. In a pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder, and a width grading mechanism comprising a fan-board, a contact member co-operating with the fan-board and connected to one of the said instrumentalities to cause width grading movements thereof, and a cam and connections for automatically varying the setting of the member on the fan-board.

20. In a pattern copying machine, four principal instrumentalities viz, a model wheel, a model holder, a cutter and a block holder, arranged for relative movement in pairs in such manner that the depth of cut in the block is controlled by the contact between the model wheel and a model held in the model holder, and a width grading mechanism comprising a fan-board, a contact member co-operating with the fan-board and connected to one of the said instrumentalities to cause width grading movements thereof, and a cam and connections for automatically varying the setting of the member on the fan-board, periodically in time relation to the rotation of the model.

21. In a pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder, and a width grading mechanism comprising a member on the model side of the machine constructed and arranged for movement proportional to the model radius being reproduced at any instant, a second member connected to a principal instrumentality and co-operating with the first-named member to

multiply the said movement while transmitting it to the said instrumentality for width grading purposes, and mechanism for automatically changing the multiplication factor during the production of a piece of work.

22. In a pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder, and a width grading mechanism comprising a member on the model side of the machine constructed and arranged for movement proportional to the model radius being reproduced at any instant, a second member connected to a principal instrumentality and co-operating with the first-named member to multiply the said movement while transmitting it to the said instrumentality for width grading purposes, and mechanism for automatically changing the multiplication factor periodically during the production of a piece of work, the period being equal to that of the model revolution.

23. In a pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder, and a width grading mechanism comprising a fan-board, a contact member arranged to co-operate with the fan-board and connected to a principal instrumentality to transmit width grading movement thereto, a setting member for placing the contact member in adjustment in relation to the fan-board, and mechanism for automatically operating the setting member.

24. In a pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder, and a width grading mechanism comprising a fan-board, a contact member arranged to co-operate with the fan-board and connected to a principal instrumentality to transmit width grading movement thereto, a setting member for placing the contact member in adjustment in relation to the fan-board, a lever to which the setting member is also connected, and means for operating the lever to control the setting of the contact member during the production of a piece of work.

25. In a pattern copying machine, four principal instrumentalities, viz, a model wheel, a model holder, a cutter, and a block holder, arranged for relative movement in pairs in such manner that the depth of cut

in the block is controlled by the contact between the model wheel and a model held in the model holder, and a width grading mechanism comprising a fan-board, a contact member arranged to co-operate with the fan-board and connected to a principal instrumentality to transmit width grading movement thereto, a setting member for placing the contact member in adjustment in relation to the fan-board, a lever to which the setting member is also connected, the connection with said lever being adjustable to vary the setting of the contact member, and a cam and connections for operating the lever to vary the setting of the contact member during the production of a piece of work.

26. In a pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder, and a width grading mechanism comprising a fan-board, a contact member for the fan-board connected to a principal instrumentality for effecting width grading movements thereof, a circular segment placeable with its center of curvature at the neutral point of the fan-board, a link connecting the contact member with the segment, its connection with the segment being adjustable, and means for moving the segment to operate the link and thereby move the contact member from the neutral point of the fan-board.

27. In a pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder, width grading mechanism for varying the normal 1:1 reproductive movements of said instrumentalities, and cam-operated mechanism for inhibiting the action of said grading mechanism at desired intervals during the work production whereby the width grading may be restricted to arbitrary portions of the work.

28. In a pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder, a width grading mechanism, and means for multiplying the width grading movement effected by said grading mechanism by a quantity which may vary during the production of a piece of work.

29. In a pattern copying machine, four principal instrumentalities, viz, a model

- wheel, a model holder, a cutter and a block holder, arranged for relative movement in pairs in such manner that the depth of cut in the block is controlled by the contact between the model wheel and a model held in the model holder, model and work rotating means, mechanism for imparting to one of the principal instrumentalities a predetermined movement which may vary and is related to the orientation about the axis of rotation of the model radius being reproduced, and means for multiplying said movement by a factor proportional to the length of the said radius. 5
30. A copying lathe in which the various cross-sections produced in the work are governed by corresponding cross-sections of a model, comprising connections which vary during the operation of the lathe so as to vary the effect of the model upon one cross sectional dimension of the work from that upon another, the variation being proportional to the absolute dimensions of that particular cross-section being reproduced. 10
31. In a pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder, and a width grading mechanism comprising a first member attached to one of the principal instrumentalities to impart width grading movements thereto, a second member arranged for movements proportional to the model radius being reproduced, a third member arranged for arbitrarily predetermined movement, and means for transmitting to the first-named member the product of the movements of the two last-named members. 15
32. In a pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder, and a width grading mechanism comprising a first member attached to one of the principal instrumentalities to impart width grading movements thereto, a second member arranged for movements proportional to the model radius being reproduced, a third member arranged for arbitrarily predetermined cam controlled movement, and means for transmitting to the first-named member the product of the movements of the two last-named members. 20
33. In a pattern copying machine, four principal instrumentalities, viz, a model wheel, a model holder, a cutter and a block holder arranged for relative movement in pairs in such manner that the depth of cut
- in the block is controlled by the contact between the model wheel and a model held in the model holder, and a width grading mechanism comprising a first member attached to one of the principal instrumentalities to impart width grading movements thereto, a second member arranged for movements proportional to the model radius being reproduced, a third member arranged for arbitrarily predetermined cam controlled movement corresponding to the model rotation, and means for transmitting to the first-named member the product of the movements of the two last-named members. 25
34. In a pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder, and a width grading mechanism comprising a fan-board, a contact member for the fan-board connected with a principal instrumentality to impart grading movements thereto, a link attached to the contact member for moving it across the fan-board, a crank arm to which the link is adjustably attached to set the contact member, and a cam and connections for operating the crank to effect arbitrary predetermined movements of the contact member on the fan-board during the production of a piece of work. 30
35. In a pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder, and a width grading mechanism comprising a fan-board, a contact member for the fan-board constructed and arranged to impart width grading movements to one of the principal instrumentalities, and means for automatically moving the contact member to the neutral point of the fan-board during a portion of each rotation of the model whereby no width grading will be done over the corresponding portions of the model. 35
36. In a pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder, and a width grading mechanism comprising a fan-board, a contact member for the fan-board constructed and arranged to impart width grading movements to one of the principal instru- 40

5 mentalities, and means for automatically moving the contact member to the neutral point of the fan-board during a portion of the work production whereby no width grading will be done over the corresponding portion of the model.

10 37. In a pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder, and a width grading mechanism comprising a fan-board formed on a circular arc, a contact member for the fan-board, and a link (150) mounted at one end on the contact member and having its other end connected to one of the principal instrumentalities to impart width grading movements thereto, the center of curvature of the fan-board falling at the other end of the link when the axis of the model holder is on the face of the model wheel.

15 38. In a pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder, and a width grading mechanism comprising a fan-board, a contact member for the fan-board arranged to transmit width grading movement to one of the principal instrumentalities, a crank arm connected to the contact member to set it on the fan-board, the connections having provision for adjustment on the crank to provide for different width grades, and means for setting the crank to correspond with the model size, to secure the same absolute width increase for the same connection adjustment, irrespective of the model size.

20 39. In a pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder, and a width grading mechanism comprising a fan-board, a contact member for the fan-board arranged to transmit width grading movement to one of the principal instrumentalities, a graduated crank arm, a link adjustable along the graduation and connected to the contact member to set it for different width grades, a rotary cam and cam roll for controlling the crank arm to vary the setting of the contact member independently of the graduation, and a link arranged to be substituted for the cam, and to connect the axis of the cam to the cam roll on

25 the lever, to hold the crank arm in normal position to effect normal width grading.

40 In a pattern copying machine, four principal instrumentalities, viz, a model wheel, a model holder, a cutter and a block holder arranged for relative movement in pairs in such manner that the depth of cut in the block is controlled by the contact between the model wheel and a model held in the model holder, and a width grading mechanism comprising a fan-board, a contact member for the fan-board arranged to transmit width grading movement to one of the principal instrumentalities, a crank arm connected to the contact member to set it on the fan-board, the connection having provision for adjustment on the crank to provide for different width grades, and means comprising a graduated link adjustable in length by the graduation for setting the crank to correspond with the model size to secure the same absolute width increase for the same connection adjustment, irrespective of the model size.

45 41. In a pattern copying machine, four principal instrumentalities, viz, a model holder, a model wheel, a work holder and a tool, four mechanical axes to which these instrumentalities are respectively related, the distance between the cutter and work holder being controlled by the distance between the model wheel and model holder axes as determined by contact between the peripheries of the model wheel and a model held in the holder, a frame swinging about a center and carrying one of said instrumentalities and in which the said instrumentality is rotated, and means for revolving the co-operating one of the principal instrumentalities, displaced from its normal position relatively to its mechanical axis, about the said mechanical axis in uniform relation to the rotation of the instrumentality in the swing frame, irrespective of the swinging movement of the frame.

50 42. In a pattern copying machine, four principal instrumentalities, viz, a model holder, a model wheel, a work holder and a tool, four mechanical axes to which these instrumentalities are respectively related, the distance between the cutter and work holder being controlled by the distance between the model wheel and model holder axes as determined by contact between the peripheries of the model wheel and a model held in the holder, a frame swinging about a center and carrying one of said instrumentalities and in which the said instrumentality is rotated, and means for revolving the co-operating one of the principal instrumentalities, displaced from its normal position relatively to its mechanical axis, about the said mechanical axis in uniform relation to the rotation of the instrumentality in the swing frame, irrespective of the swinging movement of the frame, comprising a train of gearing between the two

instrumentalities, whereby the drive of one may drive the other, said train of gearing being constructed and arranged to absorb the movement of the swing frame without relative disturbance of its terminal members.

43. In a pattern copying machine, four principal instrumentalities, viz, a model holder, a model wheel, a work holder and a tool, four mechanical axes to which these instrumentalities are respectively related, the distance between the cutter and work holder being controlled by the distance between the model wheel and model holder axes as determined by contact between the peripheries of the model wheel and a model held in the holder, a frame swinging about a center and carrying one of said instrumentalities and in which the said instrumentality is rotated, and means for revolving the co-operating one of the principal instrumentalities, displaced from its normal position relatively to its mechanical axis, about the said mechanical axis in uniform relation to the rotation of the instrumentality in the swing frame, irrespective of the swinging movement of the frame, comprising a train of gearing between the two instrumentalities whereby the drive of one may drive the other, the said train comprising a pair of spiral gears, the slope of the spiral being arranged to absorb the swing frame movement without disturbance of the two instrumentalities.

44. In a pattern copying machine, four principal instrumentalities, viz, a model holder, a model wheel, a work holder and a tool, four mechanical axes to which these instrumentalities are respectively related, the distance between the cutter and work holder being controlled by the distance between the model wheel and model holder axes as determined by contact between the peripheries of the model wheel and a model held in the holder, a frame swinging about a center and carrying one of said instrumentalities and in which the said instrumentality is rotated, and means for revolving the co-operating one of the principal instrumentalities, displaced from its normal position relatively to its mechanical axis, about the said mechanical axis in uniform relation to the rotation of the instrumentality in the swing frame, irrespective of the swinging movement of the frame, comprising a train of gearing between the two instrumentalities whereby the drive of one may drive the other, the said train comprising two shafts, each driving one instrumentality, a third shaft extending between the said two shafts and transmitting the drive, miter gears connecting the third shaft to one of the two first-named shafts, and spiral gears connecting the third shaft to the other of the two first-named shafts, the slope of the spiral being arranged to absorb the movement of all parts due to the movement of the swing frame.

45. In a three-dimensional pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder, and a width grading mechanism comprising a lever and a member adjustable along the lever and connected to one of the said instrumentalities to cause grading movement thereof, and means for automatically varying the adjustment of the member along the lever during the production of a work piece.

46. In a three-dimensional pattern copying machine, four principal instrumentalities, viz, a model wheel, a model holder, a cutter and block holder, arranged for relative movement in pairs in such manner that the depth of cut in the block is controlled by the contact between the model wheel and a model held in the model holder, and a width grading mechanism comprising a lever and a member adjustable along the lever and connected to one of the said instrumentalities to cause grading movement thereof, and power operated means for varying the adjustment of the member along the lever during the production of a work piece.

47. In a pattern copying machine, four principal instrumentalities, viz, a model wheel, a model holder, a cutter and block holder, arranged for relative movement in pairs in such manner that the depth of cut in the block is controlled by the contact between the model wheel and a model held in the model holder, and a grading mechanism comprising a lever and a member adjustable along the lever and connected to one of the said instrumentalities to cause grading movement thereof, and power operated means for varying the adjustment of the member along the lever during the production of a work piece periodically in time relation to the model rotation.

48. In a pattern copying machine, four principal instrumentalities, viz, a model wheel, a model holder, a cutter and block holder, arranged for relative movement in pairs in such manner that the depth of cut in the block is controlled by the contact between the model wheel and a model held in the model holder, and a grading mechanism comprising a lever and a member adjustable along the lever and connected to one of the said instrumentalities to cause grading movements thereof, and a cam and connections for automatically varying the adjustment of the member along the lever during the production of a work piece.

49. In a pattern copying machine, four principal instrumentalities, viz, a model wheel, a model holder, a cutter and block holder, arranged for relative movement in

pairs in such manner that the depth of cut in the block is controlled by the contact between the model wheel and a model held in the model holder, and a grading mechanism comprising a lever and a member adjustable along the lever and connected to one of the said instrumentalities to cause grading movement thereof, and a power operated cam and connections for varying the adjustment of the member along the lever during the production of a work piece.

50. In a pattern copying machine, four principal instrumentalities, viz, a model wheel, a model holder, a cutter and block holder, arranged for relative movement in pairs in such manner that the depth of cut in the block is controlled by the contact between the model wheel and a model held in the model holder, and a grading mechanism comprising a lever and a member adjustable along the lever and connected to one of the said instrumentalities to cause grading movement thereof, and a power operated cam and connections for varying the adjustment of the member along the lever during the production of a work piece periodically in time relation to the model rotation.

51. A copying lathe in which the various cross-sections produced in the work are governed by corresponding cross-sections of a model, comprising connections and a cam for varying their effective length during the operation of the lathe so as to vary the effect of the model upon one cross-sectional dimension of the work from that upon another, the effect in a radial plane along the work being proportional to the absolute dimensions of that particular cross-section being reproduced.

52. A copying lathe in which the various cross-sections produced in the work are governed by corresponding cross-sections of a model, comprising power operated connections which vary during the operation of the lathe so as to vary the effect of the model upon one cross-sectional dimension of the work from that upon another, the effect in a radial plane along the work being proportional to the absolute dimensions of that particular cross-section being reproduced.

53. In a machine of the class described, a model wheel carriage, and means for moving the model wheel relatively to the carriage transversely to the direction of ordinary width grading movement during the production of a work piece and in predetermined time relation to the rotation of the model.

54. In a machine of the class described, a model wheel carriage, and means operating cyclically in time relation to the model rotation for moving the model wheel relatively to the carriage transversely to the direction of ordinary width grading movement.

55. In a machine of the class described, a model wheel carriage, and means for impart-

ing to the model wheel a movement relative to the carriage, said movement being in the plane of the model cross-section being reproduced, and being also in a direction transverse to the direction of ordinary width grading movement.

56. A copying lathe in which the various cross sections produced in the work are governed by corresponding cross sections of a model, comprising a cam and members controlled by it for controlling the relation between a given cross section of the model and its reproduction in the work, the areas of the reproduced cross sections increasing when the cross sections themselves increase in area, but not being geometric reproductions in shape.

57. In a pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder to effect normal 1:1 transverse reproductive movements of said instrumentalities, and means for varying the normal 1:1 reproductive movements of said instrumentalities comprising a cam constructed and arranged to inhibit the said variation of the normal 1:1 reproductive movements of said instrumentalities at desired intervals during the work production whereby such variation may be restricted to arbitrary portions of the work irrespective of the shape of the model used.

58. In a pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder to effect normal 1:1 transverse reproductive movements of said instrumentalities, and means for varying the normal 1:1 reproductive movements of said instrumentalities comprising a cam constructed and arranged to inhibit the said variation of the normal 1:1 reproductive movements of said instrumentalities at desired intervals during the work production whereby such variation may be restricted to parts of the work other than the bottom.

59. In a pattern copying machine, four principal instrumentalities, viz, a model wheel, a model holder, a cutter and a block holder, arranged for relative movement in pairs in such manner that the depth of cut in the block is controlled by the contact between the model wheel and a model held in the model holder to effect normal 1:1 transverse reproductive movements of said instrumentalities, and means for varying the

normal 1:1 reproductive movements of said instrumentalities comprising a cam constructed and arranged to inhibit the said variation of the normal 1:1 reproductive movements of said instrumentalities at desired intervals during the work production whereby such variation may be excluded from all

parts of the work lying between two planes intersecting in the axis of rotation of the work.

In testimony whereof I have signed my name to this specification.

LAURENCE E. TOPHAM.
